ADJUSTABLE CONTACT STRUCTURE FOR PERIODIC SWITCHES

Filed April 11, 1949

UNITED STATES PATENT OFFICE

2,557,197

ADJUSTABLE CONTACT STRUCTURE FOR
PERIODIC SWITCHESDonald O. Nelson, Los Angeles, Calif., assignor to
Bendix Aviation Corporation, South Bend, Ind.,
a corporation of Delaware

Application April 11, 1949, Serial No. 86,815

2 Claims. (Cl. 200—25)

1 This invention relates to sonic echo sounders of the type in which an indicator (such as a lamp or a stylus) is moved continuously at a constant speed through a closed path, and a switch synchronized with the indicator movement closes a circuit to transmit a sonic pulse while the indicator is passing a predetermined point in its path, the echo of the pulse energizing the indicator to show its position at the time the echo is received. The indicator moves past a distance scale, and since the distance traversed by the indicator between the time of closure of the switch and the return of the echo is a measure of the depth, the switch closure must be accurately phased with respect to the indicator movement if the position of the indicator at the time of receipt of the echo is to be correctly shown by the scale.

An object of the invention is to provide a simple, reliable and easily and accurately adjustable switching mechanism for echo sounders of the type described.

Other more specific objects and features of the invention will become apparent from the description to follow.

Briefly, the switch construction of the invention comprises a drum, preferably of insulating material, that is mechanically coupled to the indicator for rotation in synchronism therewith, which drum has a helically extending conductive segment in its surface, in combination with one or more stationary brushes which ride on the drum so that each time the segment passes the brushes it momentarily completes a circuit therewith. To obtain the proper phasing of the contact closure with respect to the position of the indicator, the brushes are made movable with respect to the drum. An obvious method and one used in the past has been to provide for adjusting movement of the brushes tangentially with respect to the drum, the drum in such installations having a segment extending parallel to the drum axis. However, tangentially adjustable brushes are objectionable for the reason that the brushes have an appreciable area of contact with the drum and wear concave to conform with the curvature of the drum. Any tangential movement of the brush changes the contact thereof with the drum from surface contact to line contact along one edge of the brush, until the brush has again worn to fit the drum. This arrangement has proven unsatisfactory in practice because any readjustment of the brushes creates a new contact condition that does not stabilize until the brushes have again worn to fit the drum.

The aforementioned defect of prior devices is

2 avoidable by making the brushes movable in an arcuate path concentric with respect to the drum axis instead of tangentially, but such an arrangement is more complicated mechanically and undesirable for that reason.

In accordance with the present invention, the objectionable features of both tangential and arcuate adjustment are avoided by extending the contact segment helically along the drum instead of straight across the drum, and providing for adjusting movement of the brushes parallel to the drum axis. By virtue of the helical direction of the segment the timing can be varied by axial movement of the brushes without altering the contact area between the brushes and the drum.

A particular embodiment of the invention will now be described with reference to the drawing, in which:

Fig. 1 is a front elevational view of an echo depth sounder incorporating the invention, with the door of the sounder open;

Fig. 2 is a front elevational view, drawn to a larger scale, of the portions of the sounder related to the present invention;

Fig. 3 is a plan view of the contact mechanism in accordance with the present invention; and

Fig. 4 is a schematic diagram illustrating the general circuit involved in the depth sounder of the type illustrated.

Referring to Fig. 1, the depth sounder there depicted comprises a casing 10 having a front door 11 containing a window 12 through which a moving chart 13 of the recorder is visible. This chart 13 is shown as being stretched around two rollers 14 and 15 which support an intermediate section of the chart against a backing plate 16 (Fig. 2) of electrically conductive material.

The chart 13 is gradually moved from right to left by any suitable winding mechanism the construction of which is not pertinent to the present invention.

Positioned in front of the flat portion of the chart 13 and supported for rotation in a plane parallel to the chart is a recording arm 17 which carries on one end a stylus 18 which is swept across the chart 13 periodically by rotation of the arm.

The instrument comprises a frame 20 which may be secured as by screws 21 to the casing 10, this frame 20 having a downwardly depending tubular member 22, the lower end of which supports a bearing member 23 which in turn rotatably supports the arm 17. The arm 17 may be rotated by a shaft 24 which extends down through the member 22 and has on its lower end a spiral

gear 25 which meshes with a spiral gear 26 on the shaft on the recording arm 17. The exact construction of the arm supporting and rotating members is not pertinent to the present invention.

Near its upper end, the shaft 24 is shown rotatably supported by a ball bearing 28, and above this bearing it has secured to it a drum 29. Above and beyond the drum 29 the shaft 24 is shown as carrying a spiral gear 30 which meshes with a spiral gear 31 on the drive shaft of a constant speed motor 32.

The drum 29 constitutes a part of the switch construction of the invention and is preferably formed of some hard insulating material except for a conductive segment 33 that extends helically thereacross, the surface of the segment being flush with the peripheral cylindrical surface of the drum.

The drum cooperates with a pair of brushes 34 and 35 respectively which are secured to the ends of springs 36 which are supported by and extend from a brush support 39. Each spring 36 may have a longitudinal slot 36a therein through which screws 38 and 37 extend into the support 39, the support being of insulating material so as not to short circuit the brush springs. To provide additional spring tension for urging the brushes against the drum second springs 40 may be provided overlying the springs 36 and adjustable by means of the screws 38. Lugs 42 on the ends of the springs 36 opposite the brushes may be provided for making electrical connection to the brushes. By loosening the screws 37, the springs 36 and their associated brushes can be adjusted tangentially of the drum 29 for the purpose of adjusting the length of the transmitted pulse, as will be explained later.

The brush support 39 is supported for movement only in direction parallel to the drum 29. Thus it has a pair of holes 45 therein through which extend pins 45 which are anchored at one end to the frame 20. To adjustably move the brush support 39 axially of the drum 29 an adjusting screw 48 is shown having a threaded portion threaded through the support 39 and having an unthreaded portion 48a extending through a hole provided therefor in the frame 20. Flanges 48b and 48c on the screw 48 engage the opposite faces of the frame 20 to prevent longitudinal motion of the screw 48 in response to rotation thereof, so that when the screw is rotated the support 39 is moved in one direction or the other along the supporting pins 45.

Referring to the schematic diagram of Fig. 4, the two brushes 34 and 35 are shown connected by leads 50 and 51 respectively to a transmitter 52 which is energized in response to interconnection of the brushes 34 and 35 by the contact segment 33 to develop a sonic pulse which is applied over conductors 53 and 54 to a transducer 55. The compressional wave transmitted by the transducer 55 is transmitted down through the water to the bottom and reflected back to the transducer where it produces a corresponding electrical wave which is applied back over the conductors 53 and 54 to a receiver 56 which is connected in multiple with the transmitter 52 across the conductors 53 and 54. The receiver may contain an amplifier and rectifier which applies a high potential pulse over a conductor 57 and a brush 58 to the arm 17 and the stylus 18. As previously mentioned, the portion of the chart 13 that is traversed by the stylus 18 is supported by the conductive backing plate 15 which may be

connected to ground and thereby complete a return circuit back to the receiver 56. The chart may be of a special paper which responds to the potential between the stylus 18 and backing plate 16 to produce a mark on the paper.

It will be noted that the output of the transmitter 52 is applied not only to the transducer 55 but also to the receiver 56 so that the latter delivers a high voltage marking pulse to the stylus both at the time of transmission of the signal and at the time of reception of the echo. Referring to Fig. 2, when the transmitted pulse is properly timed it produces a continuous line 60 along the upper edge of the scale on the chart 13, and the echo produces another line 61 which is spaced from the line 60 at any point a distance corresponding to the depth being measured.

When the zero adjustment is correct, the line 60 falls on the zero line of the scale on the chart. If the impulse is transmitted too soon, both the lines 60 and 61 will be shifted upwardly so that they will not be properly coordinated with the chart scale. If the impulse is transmitted too late the lines 60 and 61 will be downwardly displaced with respect to their proper positions on the chart scale. Accurate adjustment can be effected with the present invention by turning the adjusting screw 48 to shift the brush carrier 39 upwardly or downwardly and thereby vary the time when the two brushes are contacted by the helical segment 33. It will be apparent that such adjustment does not alter the contact area between the drum 29 and the brushes 34 and 35.

It has been previously indicated that the length of the pulse transmitted can be varied by shifting one or the other of the brushes 34-35 tangentially with respect to the drum 29 by means of the clamping screws 37. With both brush springs 36 of substantially the same length, and the drum 40 rotating clockwise (with reference to Fig. 3) the segment 33 will contact the brush 34 before it contacts the brush 35 and will leave the brush 34 before leaving the brush 35. By making the spring of the brush 35 slightly shorter than the spring of brush 34, both brushes can be made to make and break with the segment 33 substantially simultaneously, under which condition the pulse will be of maximum length and determined by the width of the segment 33 and the corresponding width of the brushes. By shifting either brush 34 or 35 tangentially relative to the other from the position of maximum contact, as described, the length of the pulse can be shortened to any desired extent, the limit being reached when the segment leaves one brush before contacting the next. These tangential adjustments of the brushes alter the contact area between the adjusted brush and the drum, which is objectionable for reasons previously mentioned. However, such adjustment need be made only at the time of installation and need not be disturbed thereafter. On the other hand, the adjustment of the timing, which is accomplished by turning the screw 48, may have to be done at unpredictable intervals due to various factors, and it is highly desirable to be able to make this adjustment without altering the contact areas of the brushes.

The present invention is equally applicable to depth recorders employing a stylus 18 as the indicating device and to sounders of the non-recording type in which the indicator may be a rotating lamp that is flashed when energized. Hence, where used in the claims, the expression "indicator" is intended to refer to either

a stylus for producing an indication on a record sheet, or a lamp or other device for producing a visible indication other than a mark on a chart.

Although for the purpose of explaining the invention, a particular embodiment thereof has been shown and described, obvious modifications will occur to a person skilled in the art, and I do not desire to be limited to the exact details shown and described.

I claim:

1. The switch construction comprising: a drum and means for rotating it, said drum having a cylindrical surface containing a contact segment extending helically in said surface; two brushes spaced from each other in the axial direction of the drum and bearing against said drum surface for periodically contacting said segment in response to rotation of the drum, and interconnecting the brushes only during simultaneous contact of both brushes with said segment; a support for said brushes; means supporting said brush support for movement parallel to the axis of said drum and against movement tangentially of said drum; means for adjustably moving said brush support parallel to the drum axis whereby the rotative position of the drum at

the time of contact between said brushes and said helical segment can be varied without altering the contact angle between the brushes and the drum; and means supporting said two brushes on said support for relative tangential adjusting movement whereby the period of simultaneous contact of both brushes on said segment can be varied.

2. Apparatus according to claim 1 in which said brushes have substantially parallel front and rear edges extending parallel to the edges of said segment during contact therewith.

DONALD O. NELSON.
